UNITED STATES PATENT OFFICE

CHARLES REINHOLD, OF GENEVA, SWITZERLAND

DEVICE FOR REMOVING WHEELS FROM THEIR AXLES

Application filed March 27, 1930, Serial No. 439,347, and in Switzerland April 8, 1929.

The object of this invention is to provide an arrangement for the detachment of motor car wheels, aircraft propellers, etc. from their supports.

It is characterized by the fact that it comprises in combination a cylinder of relatively large diameter intended to be temporarily connected to the wheel, the propeller, or the like, a piston displaceable in the cylinder of relatively small diameter communicating in a permanent manner with the first, a piston displaceable in the second cylinder and actuated by a threaded member, the whole being arranged in such manner that on rotating the threaded member in the desired direction, there is forced into the large cylinder fluid filling the two cylinders, and producing relative movement of the large cylinder and of the corresponding piston by means of which the detachment takes place.

The attached drawings show by way of example two methods of carrying out the invention.

Fig. 1 is a longitudinal axial section of a first method of carrying out the invention.

Fig. 2 is a plan view of Fig. 1.

Fig. 3 is a longitudinal axial section of a second method of carrying out the invention.

Figs. 4 and 5 are detail views of Fig. 3.

Fig. 6 shows a variation of detail.

The first form of construction comprises a metallic body 1 in which are arranged the two cylinders 2, 3 of unequal diameters communicating in a permanent manner one with the other. The large cylinder 2 contains the piston 4 which functions to bear on the axle of the wheel or the shaft of the propeller; this piston 4 is surmounted by a cup leather 6 which is however not fixed to said piston which latter is guided by a ring 9 screwed into the body 1. The piston 4 is under the action of a spiral spring 10 disposed in the cylinder 2 between such piston and the ring 9. With regard to the small cylinder 3, this contains a piston 5 in contact with a screw threaded spindle 8 fitted in the threaded opening 12 of the body 1, and provided with a manipulating handle 11; a cup leather 7 is placed under the piston 5, without being fixed thereto. The space between the two pistons

4, 5 is filled with a liquid or semi-liquid substance such as grease.

The body 1 is provided at the level of the cylinder 2, with a thread 18 intended to be screwed into the tapped part 27 of a connector 13. The latter comprises a truncated part 14 having the tapped part 27 and openings 15 intended to reduce its weight, as also a flanged portion 16. The flanged portion 16 is to be fastened to the wheel 43 to be detached for this purpose; it has five radially disposed elongated apertures 17 equally spaced, three circular openings 21 two of which are situated at 90° from each other, and from one of the openings 17, two circular openings 22 arranged at 120° from each other, and from one of the openings 17; these are all intended to allow bolts 24 to pass through, which bolts form part of the hub 23 of the wheel which is to be detached from the axle 25 constituting its support; these bolts 24 serve normally to fix the other part not shown of the wheel to the hub 23. In the centre of the flanged portion 16 is made a large circular opening 20 into which the axle and the centre part of the hub can pass.

This form of the apparatus is used as follows in order to detach a hub provided with five bolts 24 equally distributed:

The flanged portion 16 is placed on the hub 23 taking care to pass the bolts 24 of this into the openings 17, which is easy whatever may be the distance of the bolts from the axis of the axle, owing to the elongated shape of the openings, the nuts 26 are screwed on the bolts and then in its turn the threaded part 18 of the body is screwed into the tapped part 27 of the truncated piece 14. When this is done, a rotary movement is imparted to the handle 11 in the direction necessary, so as to cause the piston 5 to descend and force the fluid filling the space between 5 and 4 of the cylinder 3 into the cylinder 2. The piston 4 is thus forced out to bear on the axle 25 and consequently forces the body 1 to lift the attachment 13 and the limb 23 which thus leaves its axle even if the resistance opposing this is large, owing to the great effort developed on the piston 4. When the wheel is raised, the body 1 is unscrewed from the lat-

ter and the rod 8 is rotated in a direction contrary to the first movement; the spring 10 brings back the two pistons 4, 5 to their position of rest. The hub 23 is then separated 16 from the flanged portion 16.

The spring 10 always maintains under a certain pressure the fluid in the cylinders even when the pistons 4, 5 are in their position of rest thus carrying the cup leather, 6, 7 to be 20 kept in contact with the corresponding pistons without it being necessary to fix them thereto.

The arrangement given to the openings 17 of the flanged portion 16, permits the detachment of wheels, the bolts of which occupy positions varying in one wheel from the other with respect to their distance from the centre; the openings 15 permit the manipulation 20 of the nuts 26 even if they are very close to the part 14.

If the hub to be detached employs four bolts 24 equally spaced, these are made to pass into the openings 21 and into one of the openings 17, and the operation is then proceeded with in the same manner as above; where there are three bolts, these are introduced into the openings 22 and into one of the openings 17.

In the second form of construction (Figs. 3 to 5), the body 1 is screwed into a tapped part 31 of a sleeve 30 slit at 32, the two lips of the slot being connected and drawn together when desired by a bolt 33 and a nut 34. The sleeve 30 has at its two extremities 35, 36 of the same diameter and the same pitch but differently directed, taking a split threaded ring 37 in which are provided radial slits 38 permitting this to be rotated by means of a special spanner. The 40 ring 37 has two tapped parts 39, 40 of different diameter and pitch, capable of being adapted to the pitches of corresponding screws, such as 41 of the hub 42 of the wheel 43 to be detached.

45 A certain number of rings such as 37 are available, all being capable of being fitted in the tapped part 36 of the sleeve 30 and each having two different tapped parts, the tapped parts of one ring differing from those of the others; there is thus a series of tappings different from each other in diameter, pitch, direction of thread (right hand or left handed), the nature of the thread, these rings 37 being slit over the whole of their length.

55 To detach a wheel by the aid of the second form of construction, the following process is adopted:

If the tapped parts 35 or 36 are neither 60 adaptable to the threaded part 41 of the hub 42, being too large, a ring 37 is chosen of which one of the tappings 40 fits the threaded part 41 of the hub 42 of the wheel 43, it is screwed into the tapped part 36 of the sleeve 30 and then this latter is screwed on to the 65 body 1. It is then only necessary to operate

in the direction desired on the handle 11 in order that the piston 4, bearing on the axle 44, separates the hub 42 from the shaft.

The rings 37 may each have more than two different tappings; for example, the ring 45 of Fig. 6 has three 47, 48, 49.

In this way, it is possible to detach hubs or wheels which are different, in particular one from the other, by means of a limited selection of rings.

Even when the threaded parts 41 of different hubs are theoretically the same they often in practice have small differences one from the other. The fact that the sleeve 30 and the rings 37 are split permits of these differences being taken up by screwing or unscrewing the nut 34 of the bolt 33.

I claim:

A device for detaching automobile wheels, aircraft propellers, or the like from their support, comprising the combination of a cylinder of relatively large diameter having a liquid therein, a piston movable in the cylinder and adapted to bear by one end on the end of the support, a second cylinder of relatively small diameter communicating permanently with the first and concentric therewith, a piston movable in the second cylinder, said piston being actuated by a threaded elongation thereof, a member for connecting the larger cylinder to the object to be detached, means on the larger cylinder and on said connecting member for detachably connecting the two, an interior tapped part on the connecting member, said tapped part being split, a clamping bolt for drawing the sectors of said part together, said tapped part being adapted to receive one of a series of slotted threaded rings and engageable with one of same at a time, said slotted ring having an external thread for engaging the connecting part and an internal thread for engaging a support, the arrangement being such that by rotating the elongated threaded member in the proper direction, the liquid filling the two cylinders is forced into the larger cylinder and causes a relative movement of the large cylinder and of the corresponding piston, whereby the wheel, propeller or the like is detached from the support.

In testimony whereof I have affixed my signature.

CHARLES REINHOLD.
